LOCOMOTIVE CYLINDER AND FRAME

Edward O. Elliott, Jenkintown, Pa.

Application September 29, 1945, Serial No. 619,379

6 Claims. (Cl. 105—37)

1

This invention relates generally to three cylinder locomotives, but specifically to an integral cylinder and frame construction.

Various designs of three cylinder locomotives have been in use for many years, however several features have not been altogether satisfactory, this invention has been developed to overcome the prior objections. One of the most valuable qualities of a properly designed three cylinder locomotive, which has not received sufficient attention in the United States, in the past, is that there is no "dynamic augment" with its destructive action on the rails, when so designed. To accomplish this result the crank pins must be spaced at angles of 120 degrees and the reciprocating weights of the driving mechanism of all three cylinders must be equal. This is ably described in W. E. Dalby's book on "Counterbalancing."

Most, if not all, of the three cylinder locomotives built in the United States within the last forty years have had the three cylinders located in approximately the same transverse plane. This necessitated a relatively short connecting rod for the center cylinder and usually a kinked front driving axle even when the cylinder was elevated and set on an angle.

By locating the center cylinder well ahead of the two outside cylinders, I overcome the objections above mentioned and at the same time obtain a much longer connecting rod which approximates in weight the rods of the outside cylinders, thus assisting in providing the equality of reciprocating weights desired.

I am aware of the fact that three cylinder locomotives with the center cylinder located ahead of the side cylinders have been designed, patented and built heretofore. However most of them have been built in foreign countries, none to my knowledge in the United States. None of these were of integral construction although locomotive beds incorporating the third or center cylinder have been patented in the United States, but never built to my knowledge.

The object of this invention is to incorporate in an integral construction the three cylinders, the center cylinder located well ahead of the outside cylinders, in combination with the well known modern form of engine bed or frame. In its location the added weight of the center cylinder is minimized by the integral construction which will reduce the number of parts and surfaces which would have to be finished and connected together in the usual manner.

Another object is to provide a simple and sub-

2

stantial construction for the opening or aperture in the cylinder saddle through which operate the driving mechanism for the crank axle of the first pair of driving wheels.

Still another object is to provide for the expansive strains induced by the high pressure steam, which have caused some failures in the integral castings of the ordinary type of two cylinder locomotives, especially when combined with the integral bed. This object is obtained by conducting the live steam to the cylinders by piping entirely without the casting.

Another object is to provide for the expansive strains and also any vibration of the center cylinder by the inclusion of an expansion joint located between the steam chest of the center cylinder and the cylinder saddle.

Still another object is to so attach the center cylinder to the front frame rails that all expansive strains are eliminated or reduced.

Another object is to provide an integral three cylinder casting with extended rear frame rails to which the conventional type of bar or plate frames may be attached.

Other objects and advantages will be more apparent to those skilled in the art from the following description of the accompanying drawings in which:

Fig. 1 is a fragmentary elevation view of the portion of the locomotive showing the cylinders, steam pipes, exhaust pipes and driving mechanism for the center cylinder, attached to the crank axle;

Fig. 2 is a plan view of the parts shown in Fig. 1;

Fig. 3 is a vertical transverse section taken on the line 3—3 of Fig. 2, showing guide and cross-head;

Fig. 4 is a vertical transverse section taken on the line 4—4 of Fig. 2 showing the integral bearing pad for the valve motion rock shaft which transfers the motion from the outside eccentric arm to the combination lever for the center valve chest;

Fig. 5 is a fragmentary view of the cylinder and bed casting;

Fig. 6 is a plan view of the parts shown in Fig. 5;

Fig. 7 is a vertical transverse section taken on the line 7—7 of Fig. 6;

Fig. 8 is a plan view of a modification of the cylinder casting, showing the connection to the conventional bar frame;

Fig. 9 is a fragmentary sectional elevation taken on the line 9—9 of Fig. 8, showing one of

the several ways of connecting the cylinder structure to the bar frame;

Fig. 10 is a vertical transverse view taken on the line 10—10 of Fig. 6 showing the bearing pad for the valve motion rock shaft.

In the illustrated preferred embodiment of the invention I have shown the locomotive boiler 1 supported on the cylinder saddle 2 which saddle is integral with the bed 3 and cylinders and other brackets such as are generally associated with the modern bed casting and which are not shown as they form no part of this invention. Moreover it is to be understood that coring, ribbing and various brackets used in the art of cylinder and bed castings form no part of this invention since they are well known to those versed in the art.

The two outside cylinders 4, 4 are shown in the usual position, that is directly attached to the saddle 2, while the center cylinder 5 is located between the forward rails 6 and 7, well ahead of the saddle 2. The driving mechanism of the outside cylinders is connected to the second pair of driving wheels 8 in the conventional manner of two cylinder locomotives and is not shown neither is the Walschaert valve gear which is used for all three cylinders, excepting that portion of the valve gear for the center cylinder, shown generally at 9 Fig. 4, which transfers the motion from the outside eccentric crank to the inside steam chest; this portion of the valve gear is shown diagrammatically for clarity by heavy dot and dash lines at 9 Figs. 1 and 2.

The driving mechanism of the center cylinder 5 has the usual piston rod connected to the cross-head 10, through which the main rod 11 operates the crank axle 12 of the first pair of driving wheels 13; crank pins 14 for the right side and 15 for the left side driving mechanism are shown diagrammatically spaced at 120 degrees. Crank pins 14 and 15 are connected by forward sections of the connecting rods, not shown, with corresponding crank pins in the second pair of driving wheels 8, thus keeping the three sets of driving mechanism in synchronism with the result that the reciprocating forces balance each other and no weights need be placed in the driving wheels to counterbalance these forces, thereby doing away with the destructive "dynamic augment."

It is obvious in this design, that a relatively large opening or aperture in the cylinder saddle 2 must be provided for the driving mechanism of the center cylinder 5 to operate efficiently. In prior art where the center cylinder was located ahead of the side cylinders and the construction was of the built up type, the combination of bar frame rails, separate cylinder castings, crossties etc. introduced elements of weakness unless made unusually massive and expensive to machine. By my integral construction a very light and strong arrangement is provided and at the same time a relatively simple casting can be made due to the connection of the front 16 and back 17 stretcher walls of the cylinder saddle 2 by the longitudinal semi-tubular walls 18 with their top portion horizontal, thus providing ample room for a guide bar 19 in which the crosshead 10 can operate; ample strength is provided by the horizontal bottom wall 20 of the saddle, which is reinforced as at 21 Fig. 9.

Additional strength to the lower portion of the cylinder saddle is provided by the extension of the horizontal bottom wall 20 of the saddle forward and beneath the center cylinder 5 to the point 22 and rearward connecting the lower por-

tion of the bed 3 to the point 23; the upper horizontal wall 24 connects the two side frame members and is carried back to the point 25; points 23 and 25 are determined by the need of clearance for the main rod 11 of the center cylinder mechanism.

An opening in the front rails 6 and 7 for servicing the crosshead 10 and front end of main rod 11 is shown at 30, Fig. 5. The front rails 6—7 are inclined inward in order to provide clearance for the forward truck wheels 26, this brings the top flange of rail 6 in so close relation to the usual steam ports from the steam chest 27 of the center cylinder 5, as shown at 28 Figs. 6 and 7 that it obviously would be difficult to provide any feasible method of attaching the center cylinder to the front rail except it be that of an integral casting. It should be noted that the steam chest 27 is located a substantial distance to one side of the center cylinder 5 in order that the operation of the valve gear for that cylinder, may not impose excessive eccentric and torsional strains on the valve motion rock shaft 9 and its bearing pad 42.

In addition to being cast integral with the front rail 6, cylinder 5 is secured to the bottom horizontal wall plate 28 of the saddle 2 in the same manner and also by the somewhat flexible web plate or bracket 29 to the front rail 7. This provides a strong anchorage for the cylinder and at the same time permits reduction of the expansion strains through the flexure of the web 29 acting in conjunction with front rail 7; to which it is attached midway between the front bumper and saddle 2.

Due to the attachment of the center cylinder to the somewhat more flexible front rails there will be some vibration of said cylinder in relation to the saddle 2; therefore an expansion joint 32, Fig. 1, is inserted in the pipe between the exhaust steam chamber 31 and the saddle 2. This will also take care of expansion due to the fluctuating temperature of the exhaust steam.

To minimize any expansive strains in the integral cylinder and bed casting, all live high pressure steam passages except the conventional ones between the steam chests and cylinders and the inlets to the steam chests, have been kept outside of the casting. The steam is conducted in the usual manner from the boiler through the steam pipes 36—36 to the T connections 37—37 of the steam chests. To the front outlets of these T's are attached the steam pipes 38—38 leading to the T connection 39 on the steam chest 27 of the center cylinder 5; these two pipes 38—38 also provide a suitable reservoir for the steam supply to the center cylinder 5, thus reducing fluctuating of the pressure. The curvature in pipes 38—38 takes care of the expansion.

All of the exhaust steam passages lead to a common exhaust base 33. Those from the two outside cylinders are of the conventional type.

The valve rod for the steam chest valve of the center cylinder and which is connected to the valve motion rock shaft 9 at 40 must pass through the cylinder saddle 2; therefore a tubular passage 41, Fig. 6, preferably of steel pipe, is provided. It must necessarily pass through the exhaust passages 34' in the saddle; these are enlarged at this point to offset the reduction in area due to the pipe 41. This pipe conduit is rolled and expanded in the walls of the exhaust passages to prevent leakage.

42 is an integral bearing pad for the valve motion rock shaft, 43 is an opening in the upper

bed plate 24 through which the inner portion of the rock shaft operates.

The engine truck is preferably of the six wheel type, the better to carry the extra weight of the center cylinder and for this purpose the location of the truck center plate 44 will generally be ahead of the saddle 2 and integral with the bottom plate 20. When necessary, the bottom rail of the bed may have to be recessed as at 45, Fig. 5, to provide clearance for the back truck wheels 50 when operating on sharp curves.

When locomotives are ordered in small lots, it is often uneconomical to use the full locomotive bed casting as the expense of the design, patterns, core boxes etc. must be borne by only a few locomotives. To meet this condition the modification shown in Figs. 8 and 9 has been developed. This is a method of preserving all the valuable features above described and incorporating them in an integral structure combining the cylinders, saddle, front and rear rails with their horizontal wall plates and at the same time joining said structure to the conventional bar or plate frame 46 by a splice, in this instance shown by an extension 47 of the bar frame and bolting it to the vertical web 48 of the rear rail extension of the integral cylinder and saddle structure, the numbered parts of which, correspond to those described as applying to the full locomotive bed. A tapered key 49 in shear may add to the security of the splice or connection, the exact form of which may be of any other type and fastened to the integral structure by bolting, riveting or welding or other means and forms no part of the invention.

It will of course be understood that various changes in details of construction and arrangement of parts may be made by those skilled in the art without departing from the spirit of the invention as set forth in the appended claims.

I claim:

1. In combination, an integral three cylinder locomotive structure comprising a boiler and cylinder saddle for the two outside cylinders and their steam chests, a center cylinder and its steam chest, spaced a substantial distance ahead of said boiler and cylinder saddle, front and back frame rails spaced longitudinally apart; a longitudinal opening through said saddle; driving mechanism for a crank axle, said mechanism operating through said longitudinal opening; all walls of said longitudinal opening formed integrally with the transverse walls of the saddle; a steam chest for the center cylinder, located to one side of the longitudinal center line of the said cylinder and adjacent one of the front rails; an exhaust chamber for the steam from the steam chest of the center cylinder, formed adjacent said steam chest; said exhaust chamber being located substantially in the same horizontal plane as the said steam chest and also located substantially on the lon-

gitudinal center line of the center cylinder; said center cylinder and its steam chest being substantially joined to and incorporated with one of the front rails; a conduit connecting the exhaust chamber of the center cylinder steam chest with the exhaust passage in the cylinder saddle.

5 2. The combination set forth in claim 1, further characterized in that the conduit connecting the exhaust chamber of the center cylinder steam chest with the exhaust passage in the cylinder saddle, has an expansion joint therein.

10 3. In combination, an integral three cylinder locomotive structure comprising a boiler and cylinder saddle for the two outside cylinders and their steam chests, a center cylinder and its steam chest, spaced a substantial distance ahead of said boiler and cylinder saddle, the steam chest for said center cylinder having formed integral therewith an exhaust chamber, said exhaust chamber being located substantially in the same horizontal plane as the steam chest for the center cylinder and also located substantially in the same longitudinal vertical plane as the center cylinder.

15 25 4. In combination, an integral three cylinder locomotive structure comprising a boiler and cylinder saddle for the two outside cylinders and their steam chests, a center cylinder and its steam chest, spaced a substantial distance ahead of the said boiler and cylinder saddle, front and back frame rails spaced longitudinally apart; a bottom horizontal plate connecting the lower portions of the said front rails; the center cylinder and its steam chest being substantially joined to and incorporated with one of said front rails and the said bottom horizontal plate.

30 35 5. The combination set forth in claim 1, further characterized in that the said back frame rails are joined to bar or plate main frames at a point ahead of the pedestals of the first pair of driving wheels, said juncture being made substantially as shown and described.

30 40 45 6. The combination set forth in claim 1, further characterized in that the back frame rails, spaced longitudinally apart, are connected at their top and bottom by horizontal plates, said back frame rails forming the juncture with the bar or plate frames, substantially as shown and described.

50 EDWARD O. ELLIOTT.
